DESIGN FOR A BOTTLE

Frederick S. Wildman, New York, N. Y., assignor to Bellows & Company, Inc., New York, N. Y., a corporation of New York

Application June 7, 1937, Serial No. 69,713

Term of patent 14 years

To all whom it may concern:

Be it known that I, Frederick S. Wildman, a citizen of the United States, residing at New York, New York County, New York, have invented a new, original, and ornamental Design for a Bottle, of which the following is a specification, reference being had to the accompanying drawing, forming a part thereof, and in which:

Fig. 1 is a face view of a bottle showing my new design;

Fig. 2 a side view of the same; and

Fig. 3 a top plan view of the same.

I claim:

The ornamental design for a bottle as shown.

FREDERICK S. WILDMAN.
